CHARLES F. HUMPHREYS, OF LANCASTER, PENNSYLVANIA, ASSIGNOR TO ARMSTRONG CORK COMPANY, OF LANCASTER, PENNSYLVANIA, A CORPORATION OF PENNSYLVANIA

METHOD OF MAKING FLEXIBLE HARD SURFACED COVERING

Application filed May 16, 1929. Serial No. 363,581.

This invention relates to the manufacture of flexible hard surfaced coverings, and is herein particularly described as applied to the manufacture of inlaid linoleum. It provides a method whereby a wide variety of patterns can be reproduced at low cost.

There are two general methods of making inlaid linoleum. In one of them the linoleum mix, in granular form, is applied through stencils to the burlap back so as to make up the desired pattern, the mix then being consolidated under a press. In the other method, pattern elements are die-cut from sheets of linoleum mix and are applied to a backing. This latter method is adaptable to continuous machine production, and a rotary type of machine for carrying out such process is well known in the art.

Machines of the rotary type are very expensive and must be operated continuously and at relatively high speed to be economically justifiable. Unfortunately such machines, as heretofore constructed, have only been capable of producing linoleums in a limited field. While it is possible to vary the patterns by changing the die rolls employed, the machine as now constructed are capable of applying only a relatively small number of colors. This limitation is a serious one because the trend is toward linoleums employing a variety of colors and particularly to linoleums having haphazard contrasting spots of color embodied in the design.

The rotary machine consists essentially of a large drum which carries the backing or web to which the pattern elements are to be applied. These pattern elements are cut out of unbacked sheets or webs of linoleum mix by means of die rolls which lie substantially tangent to the first mentioned roll. Each die roll must be supplied with a web of linoleum mix which is as wide as the product of the machine.

Each die roll is effective for cutting up this web into small pieces. Those pieces which form no part of the final design are knocked out as scrap and the remaining pieces are applied by the die roll to the

backing. There must be a separate die roll for each color of material employed. It follows that if three colors are employed, the amount of scrap is twice the area of the goods, and if four colors are employed, the amount of scrap is three times the area of the goods. The amount of scrap may be expressed by the following formula:

Scrap = Area of product $(N-1)$, where N equals the number of colors employed.

Sometimes this scrap may be milled and used over again, but, particularly in the lighter colors and in the marbles and jaspés, it is difficult if not impossible to use the scrap because of the difficulty of controlling color.

From the foregoing it is clear that the ordinary rotary machine is inherently of such character that designs employing small relatively widely spaced spots of color cannot be economically produced thereon. It is, however, highly desirable to produce linoleum of this character at the speeds which are obtainable only by the rotary machine.

I provide for applying pattern elements by the die rolls to a portion only of the web or backing. Therefore, when the material leaves the drum of the machine, part of the web is exposed. Some or all of the exposed parts may be filled in by hand so as to provide brightly colored spots, or, if desired, they may be left uncovered, thus providing a linoleum having portions at different surface levels.

The pattern on linoleums made by rotary machines usually repeats itself every 18 inches. The circumference of the die rolls employed is usually 54 inches and each die roll, as is well known, is provided with scrap ejectors which are actuated by scrap rolls lying within the die rolls. The size of the scrap roll is usually such that it makes three revolutions for each revolution of the die roll, thus giving the repeat length of one-third of 54 inches, or 18 inches. While in certain of those cases where contrasting spots of color are to be filled in by hand it may be satisfactory to insert such a spot every 18 inches, this is ordinarily undesirable because the repeat of the pattern is

brought home very forcefully to the observer by the presence of the bright spots.

I therefore provide for applying to some of the recurrent uncovered web areas elements which merge into the general background of the design, and apply the contrasting design elements at intervals which are a multiple of the repeat length of the general pattern. This is highly advantageous as it has the effect of multiplying by several times the repeat length of the pattern, thus materially improving its appearance and sales value. For example, every third uncovered area may be filled with a pattern element of contrasting color and the two intermediate areas may be filled with colors corresponding to colors applied by one or more of the die rolls.

After the design elements have been filled in by hand, the material is calendered, thus consolidating all of the pattern or design elements with the web and with one another.

If desired, the pattern elements may be left spaced apart so as to expose portions of the background. This is particularly effective in those patterns which are made in imitation of tiling. In such cases the web is made of a color to simulate mortar joints and the applied pattern elements are made of a shape and color to correspond to tiles.

By the use of my process a pattern element simulating a brightly colored tile may be dropped in at such intervals as are designed. This relieves the monotony of the goods and materially improves its salability.

If desired, the design elements which are applied may be laid on over elements which have been applied by the machine. This is very advantageous in the production of special patterns.

My process involves relatively little expense because in the operation of a rotary machine there are always a number of inspectors who check up on the material as it leaves the rotary machine proper and before it passes to the calender. These inspectors can fill in those areas which have been left exposed by the machine itself.

In the accompanying drawings illustrating the present preferred embodiment of the invention and certain modifications thereof,

Figure 1 is a diagrammatic view illustrating the rotary machine,

Figure 2 is a top plan view of a part of a length of linoleum in process of manufacture and embodying my invention,

Figure 3 is a section through a piece of linoleum made according to my invention, and of the type wherein a portion of the base material is exposed between pattern elements, and,

Figure 4 is a perspective view of still another form of linoleum, showing a pattern element applied over one which was applied to the base material by the machine.

The machine shown in Figure 1 comprises a main drum 2 having cooperating die rolls 3. Each die roll is supplied with a web 4 of linoleum mix supplied from a calendar 5 by belts 6. As the web of linoleum mix reaches the die roll it is engaged by a platen roll 7.

As is well understood in this art, each die roll is provided with cutting knives on its peripheral surface, which knives substantially cut through the web 4 as it passes between the die roll and the platen roll 7, so that the entire web is cut up into pieces.

As is also well understood in this art, the excess material is ejected by means of a scrap roll 8, lying within the die roll and provided with pins which actuate strippers in the die roll. These strippers normally lie below the level of the cutting edges of the die roll knives, but when engaged by the pins of the scrap roll 8 they are pushed outwardly to eject the scrap material into a trough or conveyor 9, by which the scrap is taken away from the machine. Brushes 8a engage the material as it is pushed outwardly by the strippers and aid in removing the scrap from the die roll.

Upon continued rotation of the die roll 3, the remaining pieces of the web 4 are pressed outwardly by a pattern roll (not shown) working on the strippers of the die roll, so that said remaining pieces are applied to a web 10 of base material extending around the drum 2. The web 10 usually consists of a burlap backing covered by a linoleum mix of such character that it is somewhat "tacky", whereby the pattern elements readily adhere to it.

Each die roll 3 is effective for supplying a different color of linoleum to the web and, as above stated, in the rotary machines as heretofore employed, the entire surface of the web has been covered. According to the present invention, however, portions of the web are left uncovered. This is shown, in a conventional tile pattern, at the left hand side of Figure 2. The backing material is indicated at 10 and the general pattern is made up of squares lying side by side. The squares are shaded in dotted lines and, as shown by this shading, the general pattern is made up of three colors, the different colors being applied by the three different die rolls shown in Figure 1. The scrap rolls are arranged to eject scrap material in such manner that squares 11 are left uncovered, the web 10 showing through.

As the material leaves the drum 2 it passes over an inspection table 12 where the squares 11 are filled in. This work is done by inspectors or other workers standing alongside the table 12. They will employ previously died-out squares of material and fill in the squares 11 as the linoleum moves past. The pattern shown in Figure 2 is made up of 3 inch squares, so that the openings 11 re-

cur at 18 inch intervals. This, as above stated, is the normal pattern repeat distance on commercial rotary machines.

At the right hand side of Figure 2 there is shown the linoleum with the squares 11 entirely filled in. The heavily shaded squares represent pattern elements of contrasting color. It will be noted that one of such squares, numbered 13, has been used to fill in one of the squares 11 and that two squares 14 of colors corresponding to colors applied by the die rolls have been filled in the next two squares 11. These squares 14 merge into the general background and are not distinguishable from the squares which were applied by the machine. The squares 14 are in turn followed by a square 15 of contrasting color. In Figure 2 the squares 13 and 15 have been cross-hatched so as to 20 show them as different from one another in color, and it will be understood that in this way many desirable effects may be obtained.

Figure 3 shows a linoleum comprising a burlap back 16 covered by a linoleum mix 17, the backing 16 and the mix 17 forming the base web, and pattern elements 18 applied to this web. The pattern elements 18 are spaced apart as shown in the drawings so as to leave parts of the web showing 30 through. This is particularly desirable in those patterns made in simulation of tile. I have indicated at 19 a pattern element of contrasting color which is to be laid in by hand.

From the foregoing it will be seen that 1 discharge an amount of scrap greater than the area of the product times one less than the number of active die rolls.

In Figure 4 I have shown a linoleum of 40 the same general character as that illustrated in Figure 3, except that one of the pattern elements 18' has had laid upon it a pattern element 20, which, as hereinafter described, is consolidated with the pattern element 18' so as to form an integral part of the linoleum.

After the squares have all been filled in (in a linoleum of the type shown in Figure 2), or after the overlying design elements 50 have been applied (as in the case of the linoleums shown in Figures 3 and 4), the material passes to a calender. This calender consists of a main roll 21 having a blanket 22 extending around a portion of the circumference thereof. The blanket 22 is backed by pressure rollers 23 and the linoleum passes between the blanket and the drum 21 where the several parts are compressed and consolidated. After leaving 55 the calender the product goes to the stove for curing in the usual way.

My pending application Serial No. 361, 095, filed May 7, 1929, relates to a surface covering having pattern elements arranged 65 to provide a repeating pattern and other

elements arranged at intervals which are a multiple of the repeat length of the general pattern. The broad invention of applying pattern elements to the web and then applying further pattern elements to the 70 first mentioned pattern elements is described and broadly claimed in the pending application of John Emig, Serial No. 361,076, filed May 7, 1929, now Patent 1,824,041.

A machine for automatically applying died-out pattern elements to the web in such manner that portions thereof are exposed only at intervals which are a multiple of the repeat distance as determined by the scrap roll, is described and claimed in the pending 75 application of John Wiley, Serial No. 365, 625, filed May 24, 1929, now Patent 1,873, 80 090 issued August 23, 1932.

I have illustrated and described a present 85 preferred embodiment of the invention and certain modifications thereof. It will be understood, however, that the invention is not limited to these forms, nor to the precise method of manufacture described, as it may be otherwise embodied or practiced within 90 the scope of the following claims.

I claim:

1. In the method of making a flexible 95 surface covering having a base web with overlying design elements in a machine effective for cutting a web of facing material into pattern elements and scrap, discharging the scrap and applying the several pattern elements to the base, the steps consisting in covering a portion only of the base web with said pattern elements and applying design elements to another portion of the base web by hand.

2. In the method of making a flexible 100 surface covering having a base web with overlying design elements in a machine effective for cutting facing material into pattern elements and scrap, discharging the scrap, and applying the pattern elements to the base, the steps consisting in discharging the scrap 105 in such amount that portions of the base web are uncovered as the material leaves the machine.

3. In the method of making a flexible 110 surface covering having a base web with overlying design elements in a machine effective for cutting facing material into pattern elements and scrap, discharging the scrap and applying the pattern elements to the base, the steps consisting in discharging the scrap 115 in such amount that at least some of the design elements are in non-contiguous relation with the base web showing therebetween at regularly recurring intervals when the material leaves the machine.

4. In the method of making a flexible 120 surface covering have a base web with overlying design elements in a machine effective for cutting facing material into pattern elements and scrap, discharging the scrap and 125 130

applying the pattern elements to the base, the steps consisting in discharging an amount of scrap greater than the area of the product times one less than the number 5 of webs of facing material supplied to the machine, and applying the remaining material to the base web, thus forming a material wherein a portion of the web is uncovered.

- 10 5. In the method of making a flexible surface covering having a base web with overlying pattern elements in a machine effective for cutting a web or webs of facing material into pattern elements and scrap, dis- 70
15 charging the scrap and applying the pattern elements to the base, the steps consisting in discharging the scrap in such amount that the total area of the unscraped material is less than the area of the goods, applying 80
20 such unscraped material to the web, thus leaving portions thereof uncovered, and subsequently applying pattern elements by hand to uncovered portions of the web.

6. In the method of making a flexible sur- 25 face covering having a base web with over-
lying pattern elements in a machine effective for cutting a web or webs of facing material into pattern elements and scrap, dis-
charging the scrap and applying the pattern 90
30 elements to the base, the steps consisting in discharging the scrap in such amount that the total area of the unscraped material is less than the area of the goods, applying such unscraped material to the web, thus
35 leaving portions thereof uncovered, applying to certain of the uncovered portions pattern elements which merge with the general background of the design, and applying contrasting pattern elements to other of said portions.

- 40 7. In the method of making a flexible sur-
face covering having a base web with over-
lying pattern elements in a machine effective for cutting a web or webs of facing material into pattern elements and scrap, discharging the scrap and applying the pattern elements to the base, the steps consisting in discharging the scrap in such amount that the total area of the unscraped material is less than 105
50 the area of the goods, applying such unscraped material to the web, thus leaving portions thereof uncovered, applying to certain of the uncovered portions pattern elements which merge with the general background of the design, and applying contrasting pattern elements to other of said portions, the background elements and the contrasting elements being applied in sequence, whereby a pattern repeat which is a
55 multiple of the distance between portions left uncovered is obtained.

- 60 8. In the method of making a flexible sur-
face covering having a base web with over-
lying design elements, the steps consisting in 110
65 forming a series of webs of facing material,
each web being as wide as the desired product and the webs being in different colors, cutting the several webs into pieces, laying pieces from each web on a base web so as to form an overlying pattern thereon, and dis-
charging the remainder of the webs as scrap, the total area of the pieces from the several webs applied to the base web being less than the area of such base web whereby a portion 75
70 of the base web is left uncovered.

each web being as wide as the desired product and the webs being in different colors, cutting the several webs into pieces, laying pieces from each web on a base web so as to form an overlying pattern thereon, and dis- 70
75 charging the remainder of the webs as scrap, the total area of the pieces from the several webs applied to the base web being less than the area of such base web whereby a portion of the base web is left uncovered.

9. In the method of making a flexible surface covering having a base web with overlying design elements, the steps consisting in forming a series of webs of facing material, cutting the several webs into pieces, 80
85 laying pieces from each web on a base web so as to form an overlying pattern thereon, and limiting the number of pieces so supplied as to leave a portion of the base web uncovered, discharging the remainder of the 85
90 webs as scrap.

10. In the method of making a flexible surface covering having a base web with overlying design elements, the steps consisting in forming a base web having a facing 90
95 of linoleum composition, forming a series of webs of facing material, each web being substantially as wide as the base web, cutting the several webs of the series into pieces, and laying pieces from each web on portions 95
100 only of the base web so as to form an overlying pattern thereon, the facing of the base web being exposed between overlying pattern elements.

In testimony whereof I have hereunto set 100
my hand.

CHARLES F. HUMPHREYS.
